UNITED STATES PATENT OFFICE

2,281,127

FLOAT OPERATED SWITCH

Jacob Ottis Williams, San Bernardino, Calif.

Application August 29, 1939, Serial No. 292,438

1 Claim. (Cl. 200—84)

The present invention relates to new and useful improvements in float operated switches.

An object of the invention is to provide a float operated switch which may be adjusted to close a circuit at low liquid level.

Another object of the invention is to provide a float switch which may be adjusted for closing a circuit at high or low liquid level.

Another object of the invention is to provide a switch which may be hand operated to test its operation.

Other objects of the invention are to provide a device of the aforementioned character which will be durable and reliable in use, simple in operation and which may be manufactured at low cost.

Still further objects and advantages of the invention will become apparent from a study of the following detailed description, taken in connection with the accompanying drawing, wherein like characters of reference designate corresponding parts and, wherein:

The figure is a vertical sectional view.

Referring now to the drawing in detail, it will be seen that the reference numeral 32 designates a cylindrical housing having an open bottom and a dome like top 33. The housing 32 has threaded openings 34, 35, 36 and 37 in the dome shaped top 33 thereof while another threaded opening is formed in the side of the housing 32 as at 38.

Nipples 39, 40 and 41 are mounted in the threaded openings 34, 36 and 38 and have mounted axially therein and insulated therefrom conductor elements 42, 43 and 1 which project within the housing 32 as shown in the drawing.

The conductor element 1 has formed on its bottom end an inverted T-shaped head 44 which is secured to and between the bars 3—3 of the swinging contact lever 45 through the medium of a pin 2.

The swinging contact lever 45 is composed of the bars 3—3 which are spaced apart and secured together by blocks 4 and 9 which are secured to the bars in any suitable manner. A block 5 between the bars 3—3, has a vertical threaded opening 6 therethrough and, is provided at its sides with laterally extending pins 7 each of which engages in an elongated opening 8 in each of the bars 3—3.

A push rod 10 having a threaded portion 13 for engagement in the threaded opening 6 of the block 5 is provided for swinging the contact lever 45 when actuated by a float (not shown). The push rod 10 has a square shank 14 at its top end portion upon which a winged wrench 15 is slid-

ably engaged and held against displacement by a washer 17 which is secured to the shank 14 to provide a flanged end thereon. The push rod 10 has mounted thereon a float engaging collar 11 which is adjustably secured to the push rod 10 through the medium of a set screw 12.

The winged wrench 15 has small openings formed in its wings as shown at 16.

Mounted in the threaded opening 35 is a flanged insulator sleeve 18 which is provided with threads 20. The flange portion of the insulator sleeve 18 is exteriorly of the dome top 33 and is housed in a threaded sleeve 21 which is welded or otherwise secured to the dome top 33. The sleeve 21 has an apertured ear 22 extending from one side thereof.

To protect and cover the winged wrench 15 a cap 23 is threaded engaged on the sleeve 21 and it is provided with an apertured ear 24 which, when aligned with the apertured ear 22 may be sealed to prevent unauthorized removal of the cap 23.

The insulator sleeve 18 has a slot 19 in its top side in which the winged wrench 15 is engaged to hold the same against accidental movement.

Mounted in the threaded opening 37 is a screw threaded shaft 25 the lower end of which is provided with an insulator foot 26 which is secured to the threaded shaft 25 by a set screw 27. The top end of the threaded shaft 25 extends beyond the dome top 33 and is surrounded by a threaded sleeve 28 which is welded or otherwise secured to the top side of the dome top 32. The sleeve 28 has an apertured ear 29 on one side thereof which, when aligned with an apertured ear 31 on the cap 30, is sealed to the ear 31 to prevent unauthorized removal of the cap 30.

The operation of the device is as follows:

When the push rod 10 is moved in an upward direction it forces the contact lever 45 to swing on the pin 2 and contact the block 9 with the conductor pin 43 thereby completing a circuit from the conductor pin 1 to the conductor pin 43. When the push rod 10 moves downwardly sufficiently the block 9 contacts the conductor pin 42 thereby completing a circuit between the conductor pin 1 and the conductor pin 42.

When it is desired to prevent a circuit from flowing from the conductor pin 1 to the conductor pin 43 the threaded shaft 25 is fed through the opening 37 until the insulator foot 26 is extended low enough to prevent contact of the block 9 with the conductor pin 43.

In order to adjust the push rod 10 in the block 5 the winged wrench 15 is turned, with the re-

sult that the threaded portion 13 of the push rod 10 is fed upwardly or downwardly through the block 5.

When it is desired to make a test of the switch to determine its operativeness the cap 23 is removed. A length of wire, or the like, may then be engaged in the openings 18 of the winged winged wrench 15 and employed to lift the winged wrench 15 which will in turn lift the push rod 10 and contact lever 45 and cause the block 9 to contact the conductor pin 43.

Although I have shown and described herein a preferred embodiment of my invention, it is to be definitely understood that I do not desire to limit the application of the invention thereto, and any change or changes may be made in the structure and arrangement of the several parts, within the spirit of the invention as claimed.

What is claimed is:

In a device of the character described, a float operated switch including a housing, conductor pins insulated from and projecting into said housing, an enlarged head on one of said pins, a conducting contact lever pivotally secured at one end portion to said head, a block pivotally secured to an intermediate portion of said conducting contact lever, said block having a threaded vertical opening therethrough, a threaded push rod adjustably mounted in said threaded block opening for swinging said conductor lever to close a circuit, and a wrench secured to said push rod for rotating the same into adjusted position in said threaded opening in said block.

JACOB OTTIS WILLIAMS.
